CLAIM

(57) We claim the ornamental design for a spoon, as shown and described.

DESCRIPTION

FIG. 1 is a top plan view of a spoon showing our new design. Legs 120 may be coupled to Handle 130 near Bowl 110. Legs 120 extend from Handle 130 diagonally outward, downward, and toward Bowl 110.

FIG. 2 is an enlarged side elevational view thereof.

FIG. 3 is an enlarged bottom plan view thereof.

FIG. 4 is an enlarged end view thereof; and,

FIG. 5 is an enlarged perspective view thereof.
